UNITED STATES PATENT OFFICE

MASANAO IIDA, OF NEAR TACOMA, WASHINGTON

RAIL PLATE

Application filed February 9, 1929. Serial No. 338,641.

This invention relates to the plate placed between the rail and the tie in a railroad track, and has special reference to such plates as are made in two complementary parts. The objects of my invention are, first, to provide a pair of complementary plates which, when in place, are firmly locked together, and hold the base of the rail between them; second, in which the interlocking action of the pair of plates not only secures them from separating laterally but also prevents any relative longitudinal motion therebetween; and third, which are cheap to make, easy to apply, and which effectively hold the rail in place. A further object is to prolong the life of the tie, and to keep the rail firmly attached thereto, and thereby to reduce the common cause of many accidents due to the loosening of the rail from its attachment to the tie.

I attain these and other objects by the devices and arrangements illustrated in the accompanying drawings, in which—

Fig. 1 is a cross-section of a rail mounted in my improved rail plates;

Fig. 2 is a plan of the pair of plates interlocked with each other;

Fig. 3 is an end elevation thereof;

Fig. 4 is a similar view of the tongue plate;

Fig. 5 is a section of the socket plate;

Figs. 6 and 7 are perspective views of the interlocking tongue and socket of the respective plates;

Figs. 8 and 9 are elevations of the two plates, respectively, taken from their contiguous or inner edges;

And Fig. 10 is a perspective view of the guide tool used in the assembling of the plates together under the rail.

Similar numerals of reference refer to similar parts throughout the several views.

As seen in the drawings, my improved rail plate is composed of two sections 1 and 2. The section 1 is known as the tongue plate, and the section 2 is known as the socket plate.

The two plates 1 and 2 are in all respects complementary to each other and are adapted to lie side by side under the center of the rail.

Each plate 1 and 2 comprises a flat base, adapted to lie on the tie, having a rail-gripping flange 3 extending upward and inward

from its upper surface and adapted to firmly grip over the edge of the base 4 of the rail 5. Each plate is also provided with suitable spike-holes 6 therein, through which spikes may be driven into the tie to hold the plates 55 and the rail base 4 firmly in place. The inner edge 7 of each of the plates 1 and 2 is vertical and they are adapted to butt against each other directly under the center line of the rail 5. Except, however, at the center of 60 the edge 7 of the tongue plate 1 I have provided a projecting tongue 8 and, in the center of the edge 7 of the socket plate 2, I have provided a complementary socket 9.

The tongue 8 is preferably oval in plan 65 shape, or it may be of any other contour provided that its width at the neck 10 is less than its width at a point removed outward therefrom, thus forming an acute angle between the edge 7 and the adjacent part of the tongue 70 8. The tongue 8 is, at the neck 10, substantially the full thickness of the plate 1, but its under surface 11 slopes or tapers upward towards its upper surface.

The socket 9 is of the same outline as the 75 tongue 8 and its bottom 12 slopes downward from the upper inward part to the lower edge of the vertical surface 7 of the said plate 2. Since the socket is of the same shape as the tongue, it is evident that it has two horns 13 80 extending towards each other at its outer end, said horns fitting in the acute angles above referred to. The upper edges 14 of these horns 13 may be slightly beveled off in order to permit the lower surface 11 of the tongue 85 8 to slide thereon as the two plates are pushed together.

My improved rail plate is set up in the following manner:—The rail 5 being substantially in place, the socket plate 2 is first 90 slid thereunder until the flange 3 engages and grips the base 4 of the said rail. Then the guide tool 15 (Fig. 10), comprising a plate having a deep rectangular opening 16 between its jaws 17, as shown, is slid under the rail from the same side thereof as the said plate 2, the said plate 2 fitting in the opening 16 between the jaws 17, and said jaws 17 extending beyond said plate 2 and completely 95 under the base 4 of the rail.

Then the other plate 1 is slid under the rail and between the guide jaws 17 until the tongue 8 thereof engages the upper edges 14 of the horns 13 of the socket 9. On further forcing the plate 1 inward the inclined bottom 11 of the tongue 8 forces the edge of the plate 2 slightly away from the base 4 of the rail, until the two plates 1 and 2 are in their proper relative positions, when the tongue 8 will snap down into the socket 9 and both plates will then lie at the same level.

The two plates 1 and 2 are thus locked together and no relative motion can be had between them, either longitudinal or transverse, such motion being prevented by the edges of the tongue engaging the edges of the socket 9 and of its horns 13.

Then the tool 15 may be removed and suitable spikes may be driven through the holes 6 in the plates and thereby secure them and the rail base on the tie. The tool 15 may then be used for placing the next pair of plates in position under the rail.

It will therefore be seen that the two plates 1 and 2 are firmly locked together and that they are both secured to the tie, and that they both securely clamp the rail base between them to hold the rail firmly in place. Since the flanges 3 hold the rail firmly, it follows that the plates cooperate to give the rail a wider base than if no such plate were used or than if there were no firm clamping flanges on said plates and the whole reliance were placed on the spikes.

Having described my invention, what I claim is:—

1. In a rail plate, the combination of a pair of complementary plates adapted to lie side by side under the rail, the contiguous edges thereof being vertical and in contact with each other; a pair of complementary gripping flanges formed on said plates and adapted to engage and grip the base of the rail between them; a socket formed in the upper side of the one plate and having an outwardly-downwardly inclined bottom extending to the contiguous edge of said plate; two horns jutting into said socket at said contiguous edge, whereby the neck of said socket is narrowed; and a complementary tongue extending from the contiguous edge of the other plate and lying in said socket and having an outwardly-upwardly inclined bottom, adapted to lie on the said inclined bottom of said socket, said tongue having a narrowed neck adapted to fit between said horns of said socket.

2. In a rail plate, the combination of a pair of complementary plates adapted to lie side by side under the rail, the contiguous edges thereof being vertical and in contact with each other; a pair of complementary gripping flanges formed on said plates and adapted to engage and grip the base of the rail between them; a socket formed in the

upper side of the one plate and having an outwardly-downwardly inclined bottom, and extending to the contiguous edge of said plate; and a complementary tongue extending from the contiguous edge of the other plate and lying in said socket and having an outwardly-upwardly inclined bottom, adapted to lie on the bottom of said socket.
